E. L. JOHNSON

DOOR CONSTRUCTION FOR FLASH LIGHT APPARATUS

Filed Oct. 22, 1921

Patented Apr. 3, 1923.

1,450,502

UNITED STATES PATENT OFFICE.

EVERARD L. JOHNSON, OF PATCHOGUE, NEW YORK.

DOOR CONSTRUCTION FOR FLASH-LIGHT APPARATUS.

Application filed October 22, 1921. Serial No. 509,674.

To all whom it may concern:

Be it known that I, EVERARD L. JOHNSON, a citizen of the United States, and residing at Patchogue, in the county of Suffolk and State of New York, have invented certain new and useful Improvements in Door Constructions for Flash-Light Apparatus, of which the following is a specification, such as will enable those skilled in the art to which it appertains to make and use the same.

This invention relates to flashlight apparatus such as used by photographers in taking photographs, and the object of the invention is to provide an improved door construction for apparatus of this class which will prevent the passage of the dust or ash and smoke discharged into a flash bag, from passing into a room or compartment in which the apparatus is used thus permitting a photographer to take a number of photographs in rapid succession; a further object being to provide a door construction for apparatus of this class which will also facilitate the re-charging of the flash gun or device usually employed, which flash gun or device is mounted in connection with one of the members of my improved door construction; and with these and other objects in view the invention consists in a door construction of the class and for the purpose specified which is simple in construction and operation and efficient in use, and which is constructed and operated as hereinafter described and claimed.

The invention is fully disclosed in the following specification, of which the accompanying drawing forms a part, in which the separate parts of my improvement are designated by suitable reference characters in each of the views, and in which:—

Fig. 1 is a back view of a flash-light apparatus of any kind or class showing my improved door construction mounted in connection therewith;

Fig. 2 a partial section on the line 2—2 of Fig. 1;

Fig. 3 a view similar to Fig. 1 but showing my improved door construction in a different position;

Fig. 4 a partial section on the line 4—4 of Fig. 1; and,

Fig. 5 a partial section on the line 5—5 of Fig. 3.

For the purpose of illustrating one use of

my improved door construction, I have shown in the accompanying drawing a flash bag 10 such as usually employed in apparatus of this class and which is mounted in connection with any kind or class of framework 11 which supports the bag 10 in an operative position, and said framework, or the central portion 12 thereof, is enlarged as shown at 13 and provided with a door opening 14 in connection with which my improved door construction 15 operates.

My improved door construction 15 comprises an inner door member 16 and an outer door member 17, the door member 16 is mounted on a spring hinge 18 of any kind or class, and said door member is provided at its periphery with a rabbet groove 19 which cooperates with the door opening 14 to form a positive closure for said door opening when the door member 16 is in the position shown in Fig. 5 of the drawing. The door member 17 is mounted upon hinges 20 and is provided at its periphery with a rabbet groove 21 to form a snug fit of said door member in the door opening 14 as shown in Fig. 4 of the drawing, and said door member is provided with a projecting hook-shaped finger piece 22 which is adapted to engage the door member 16 to move the same from the position shown in Fig. 5 to the position shown in Fig. 4 in the operation of closing the door member 17 by hand, and a suitable catch device 23 is adapted to cooperate with the door member 17 to hold it in its closed position as shown in Figs. 1 and 4.

Mounted upon the inner face of the door member 17 is a flash gun or device 24 of any kind or class, such as commonly employed in apparatus of the class under consideration, and a flexible tubing 25 is passed inwardly through the door member 17 and is connected with the flash gun or device 24 and by means of which the operative mechanisms of such gun or device may be actuated externally of the apparatus.

The central portion 13 of the frame 11 is also provided with a socket 26 by means of which a tripod or other support 27 may be connected therewith, or by means of which the apparatus may be mounted in connection with said tripod.

In the use of my improvement, the usual flash powder is placed in the flash gun or device 24 when the door member 17 is in

the position shown in Figs. 3 and 5, after which said door is closed or moved into the position shown in Figs. 1, 2 and 4 in which operation the hook-shaped finger 22 engages 5 the door member 16 and moves it into the position shown in Fig. 4 against the tension of the spring hinge 18, and the door member 17 is held in its closed position by the keeper 23.

10 The flash powder may then be ignited in the usual manner and the door member 17 opened by releasing the catch 23, in which operation the spring hinge 18 of the door member 16 will quickly operate to close said 15 door member and force the door member 17 outwardly, after which a new charge of flash powder may be mounted in the flash gun or device 24 and the above operation of opening the door member 17 and the closing of 20 the door member 16 will not allow the escape of any material amount or quantity of smoke, dust or ash of the ignited flash powder, and in this way the room or compartment in which photographs are taken will be 25 kept free from such smoke or powder, or the atmosphere of such room or compartment will remain clear, thus permitting an operator or photographer to take an unlimited number of pictures.

30 It will be understood that I am not necessarily limited to any particular form of framework for supporting the flash bag 10 nor am I limited to the specific form of bag herein shown and described, and various 35 other changes in and modifications of my improved door construction may be made, within the scope of the appended claims, without departing from the spirit of my invention or sacrificing its advantages.

40 Having fully described my invention, what I claim as new and desire to secure by Letters Patent, is:—

45 1. A door construction for flashlight apparatus comprising door members, each pivotally secured to the flash bag and co-operating with each other to close the door opening to the flash bag in different positions of said door members.

50 2. A door construction for flashlight apparatus comprising door members, each pivotally secured to the flash bag and co-operating with each other to close the door opening to the flash bag in different positions of said door members, one of said door members being adapted to be swung outwardly 55 and a flash gun mounted in connection with said door member.

60 3. A door construction for flashlight apparatus comprising door members, each pivotally secured to the flash bag and co-operating with each other to close the door opening to the flash bag in different positions of said door members, one of said door members being adapted to be swung outwardly 65 and a flash gun mounted in connection with

said door member, and means whereby said flash gun may be operated externally of the apparatus.

4. A door construction for flash-light apparatus of the class described comprising 70 two door members movably mounted in connection with the apparatus and cooperating with each other and adapted to close the door opening to the flash bag of apparatus of this class in different positions 75 of said door members, one of said door members being adapted to be swung outwardly, a flash gun mounted in connection with said door member, and means whereby said flash gun may be operated externally 80 of the apparatus, and the other of said door members being adapted to be swung inwardly of the apparatus.

5. A door construction for flash-light apparatus of the class described comprising 85 two door members movably mounted in connection with the apparatus and cooperating with each other and adapted to close the door opening to the flash bag of apparatus of this class in different positions 90 of said door members, one of said door members being adapted to be swung outwardly, a flash gun mounted in connection with said door member, means whereby said flash gun may be operated externally of 95 the apparatus, the other of said door members being adapted to be swung inwardly of the apparatus, and means for holding said first named door member in its operative or closed position. 100

6. The combination with a flashlight apparatus, of a door construction adapted to control the door opening to the flash bag of the apparatus, comprising two door members, each pivotally secured to the flash bag, 105 one of said door members being adapted to swing inwardly and the other adapted to swing outwardly and intermittently close the door opening.

7. The combination with a flashlight apparatus, of a door construction adapted to control the door opening to the flash bag of the apparatus, comprising two door members, each pivotally secured to the flash bag, one of said door members being adapted to swing inwardly and the other adapted to swing outwardly and intermittently close the door opening, and means whereby the operation of one of said door members will correspondingly operate the other. 110 115 120

8. The combination with a flash-light apparatus of the class described, of a door construction adapted to control the door opening to the flash bag of the apparatus comprising two door members adapted to intermittently close said door opening, and means whereby the operation of one of said door members will correspondingly operate the other, one of said door members being adapted to be swung externally of the ap- 125 130

paratus and a flash gun mounted in connection with said door member, and the other of said door members being adapted to be swung internally of the apparatus.

- 5 9. The combination with a flash-light apparatus of the class described, of a door construction adapted to control the door opening to the flash bag of the apparatus comprising two door members adapted to 10 intermittently close said door opening, means whereby the operation of one of said door members will correspondingly operate the other, one of said door members being adapted to be swung externally of the ap-

paratus and a flash gun mounted in connection with said door member, the other of said door members being adapted to be swung internally of the apparatus, and one of said door members being tensionally operated.

20 In testimony that I claim the foregoing as my invention I have signed my name in presence of the subscribing witnesses this 17th day of Oct. 1921.

EVERARD L. JOHNSON.
